[57] **CLAIM**

The ornamental design for a chair, as shown and described.

DESCRIPTION

FIG. 1 is a front perspective view from above and to one side of the chair of my design;

FIG. 2 is a front elevational view thereof;

FIG. 3 is a left side elevational view thereof, the right side elevational view being a symmetrical view of FIG. 3;

FIG. 4 is a back elevational view thereof; and,

FIG. 5 is a top elevational view thereof.

The broken lines of FIG. 1-4 are for environmental purposes only and form no part of the claimed design.

FIG. 1 has been shown on a reduced scale with respect to the other views.

1 Claim, 5 Drawing Sheets

FIG. 1

FIG. 3

FIG. 4
